UNITED STATES PATENT OFFICE

2,485,191

GOLF SCORE INDICATOR

Lloyd Allen Culver, Fullerton, Calif.

Application November 27, 1946, Serial No. 712,499

1 Claim. (Cl. 235—83)

1

The present invention relates to new and useful improvements in golf score indicators and more particularly to a device of this character for indicating the total strokes required by a player in playing a nine or eighteen hole golf course.

An important object of the invention is to provide a device of this character which may be conveniently carried in the pocket of a person, or which may be worn on the wrist or carried by the belt of a golfer.

A further object of the invention is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the device.

Figure 2 is a similar view with the top plate and pointer removed.

Figure 3 is a sectional view taken on a line 3—3 of Figure 1, and

Figure 4 is a bottom plan view.

Referring now to the drawing in detail, wherein for the purpose of illustration I have disclosed a preferred embodiment of the invention, the numeral 5 designates a back plate of generally circular construction and formed with extensions 6 at diametrically opposite sides provided with slots 7 to provide strap attaching loops 8 by means of which the backing plate may be secured to the wrist of a person, or attached to a belt for carrying at the waist of a person. The underside of the plate 5 is concaved as shown at 9 to conform to the curvature of the wrist.

The upper surface of the backing plate or base 5 is provided with a zero mark 10 adjacent its edge and extending in clockwise relation therefrom is a plus scale 11 reading from 1 to 10 and extending in counterclockwise relation from the zero marking 10 is a minus scale 12 likewise reading from 1 to 10.

Inner and outer concentric scales 13 and 14 are also marked on the upper surface of the base 5, the inner scale including the numbers 35 to 55 inclusive while the outer scale includes the numbers 80 to 100 inclusive. The numbers forming the several scales are positioned in radial alignment with respect to each other as will be apparent from an inspection of Figure 2 of the drawings.

2

A disc 15 is provided at its center with a downwardly projecting pin or rivet 16 which extends through an opening 17 in the center of the base 5, the lower end of the pin or rivet being upset as shown at 18 to rotatably secure the disc 15 in position on top of the base. The disc 15 is of a diameter to cover the scales 13 and 14 and to leave the scales 11 and 12 adjacent the edge of the base exposed.

10 The disc 15 is formed at diametrically opposite sides with openings 19 and 20, the opening 19 forming a window positioned above the inner circular scale 13 and the opening 20 forming a window positioned above the outer circular scale 14. The upper surface of the disc 15 is formed with a pointer 21 which projects upwardly above the surface of the disc to provide a finger grip for turning the disc and pointer on the pin 16 to swing the pointer clockwise or counterclockwise into and out of registry with the numbers of the respective plus and minus scales 11 and 12.

The underside of the disc 15 is provided with a recess 22 in which is positioned a spring projected ball 23 adapted to selectively seat in recesses 24 formed concentrically in the upper surface of the base 5 to lock the pointer in its rotatably adjusted position.

30 The present embodiment of the invention is designed for use by a golfer having an average nine hole score of 45 or an average eighteen hole score of 90, thus requiring an average of five strokes for each hole. Accordingly when the pointer 21 is at the zero marking 10 the nine hole score of 45 will appear in the window opening 19 and the eighteen hole score of 90 will appear in the window opening 20.

35 The pointer 21 is moved at the completion of each hole to indicate whether the golfer has required more or less than his five stroke average for each hole. Thus, if the golfer takes six strokes on the first hole the pointer 21 is moved to the first plus mark on the plus scale 11, and if, on the next hole he requires three strokes, that is two under his average of five for each hole, the pointer 21 is moved counterclockwise two positions until the pointer comes at rest opposite minus 1 of the minus scale 12. The player continues to keep a record of his score hole by hole until the nine or eighteen holes have been played and the final position of the pointer will indicate in the openings 19 or 20 the total number of strokes required by the golfer.

40 For golfers whose average is greater or less than 45 for nine holes or 90 for eighteen holes, 50 the numbers used on the inner and outer scales

13 and 14 are changed in accordance with their proficiency.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

I claim:

A golf score indicator comprising a base having plus and minus single stroke indicating scales thereon arranged in one arc, and also having thereon a pair of plus and minus total stroke indicating scales thereon arranged in different arcs

concentric to the arc of said single stroke indicating scales, a disk rotatably mounted on said base and concentric to said arcs, said disk concealing said total stroke indicating scales while exposing said single stroke indicating scales and having a pair of diametrically opposite sight openings therein for viewing said total stroke indicating scales therethrough, and a pointer carried by said disk for registering with said single stroke indicating scales.
